MATRIX HANDLING DEVICE

José Midulla Florez, Tampa, Fla.

Application July 23, 1934, Serial No. 736,596

13 Claims.

(Cl. 199—41)

My invention relates generally to linotype machines, and particularly to means for handling, sorting, and selecting matrices entirely by machine, and an important object of the invention is to provide a device of the character indicated wherein any desired number of different matrix feeding magazines may be used so as to eliminate entirely the necessity for changing magazines to accommodate different kinds and sizes of type. Another important object of my invention is to provide a device of the character indicated which will pick up the used matrices from the mold and automatically sort the matrices of different size and form into corresponding individual magazines, from which the matrices may be selectively fed back to the mold through operation of an electrical gate system controlled by a keyboard, the entire cycle being automatic and continuous if desired. Other objects and advantages of my invention will be apparent from a reading of the following description in connection with the drawings, wherein for purposes of illustration I have shown a preferred embodiment of my invention.

25 In the drawings:—

Figure 1 is a transverse vertical sectional view through the device showing in side elevation a bank of individual magazines arranged in accordance with the invention.

30 Figure 2 is a front elevational view of Figure 1, taken from the left in Figure 1.

Figure 3 is a transverse vertical sectional view through the lower part of two of the magazines, showing the gates.

35 Figure 4 is a longitudinal vertical sectional view through the lower part of two of the magazine tubes showing the arrangement of the feed screws in conjunction with one of the secondary sorting bars and one of the magazines fed thereby.

40 Figure 5 is a vertical transverse sectional view taken through Figure 4 approximately on the line 5—5 and looking in the direction of the arrows.

45 Figure 6 is a horizontal sectional view taken approximately on the line 6—6 of Figure 4 and looking downwardly in the direction of the arrows.

Figure 7 is a vertical transverse sectional view 50 taken through Figure 4 approximately on the line 7—7 and looking toward the left in the direction of the arrows.

55 Figure 8 is a transverse vertical sectional view taken through the sorting bar in Figure 4 and showing one of the matrices in the position there-

on which the matrix assumes as it first engages the secondary sorting bar and is supported by ramps.

Figure 9 is the wiring diagram of several of the magazines showing the magazine selecting 5 switch and the letter selecting switches.

Figure 10 is an end elevational view of the primary selector bar.

Figure 11 is a longitudinal sectional view through Figure 10 taken approximately on the line 11—11 and looking in the direction of the arrows.

Figure 12 is a transverse vertical sectional view through the keyboard showing one of the keys in operative relation to one of the switches. 15

Figure 13 is a vertical longitudinal sectional view taken through Figure 3 approximately on the line 13—13 and looking in the direction of the arrows.

It will be understood as a condition precedent 20 to a proper understanding of the following description that the molding with the matrices, the removal of the matrices from the mold, and the application of the matrices to the mold is carried on by conventional means and in the ordinary manner, the functioning of the apparatus of the invention occupying the sphere which is interposed between the taking of the matrices from the mold after the casting, and the delivery of the selected matrices to the belt conveyor 30 for delivery to the composing device. 25

Referring in detail to the drawings, the numeral 10 refers generally to the pusher device which operates to push onto and along the primary distributing or selector bar 11 the matrices 12 for 35 selective delivery into the individual chutes 1' through 8', inclusive. The bank of chutes 1' through 8' is placed under the delivery portion 13 of the primary distributor bar with the funnel upper ends thereof placed in line along and 40 beneath the portion 13 as shown in Figure 2.

The form of the portion 13 of the selector bar 11 is shown in Figure 5. The inner sides of the depending wings 15, 16 are provided with downwardly angulated teeth as indicated at 16, 17 to 45 engage the oppositely formed teeth 18, 19 on the upper part of the matrix 12. The inverted V-shaped spine 20 which is located between the portions 14, 15 is smooth so as to fail to engage the right angularly arranged teeth 21 in the top 50 notch of the matrix. Shoulders 22, 23 are arranged on the opposite edges of the matrix just below the teeth portions 18, 19 so as to rest on the shoulders 24. As the matrices are pushed along the bar 11 by the pusher 10, the matrices 55

having different arrangements of the shoulders 22, 23, and different arrangements of the teeth 18, 19, will in meeting different formations of the teeth 16, 17 on the interior of the portion 13 5 and different formations of the shoulders 24, be caused to drop from the portion 13 into the upper end of the proper chute. Although for illustrative purposes a bank of eight chutes and eight magazines have been shown, it will be understood 10 that any desired number of chutes and corresponding magazines may be provided.

Below the funnel tops of the chutes 1' through 8' the chutes are adequately reduced in size as indicated at 25 to properly convey the matrices 15 in the erect position to their lower ends. The lower end of each chute is closed as indicated at 26 and has front and back openings 27 and 28 permitting the matrices to come into contact with the left and right hand screws 29, 30, respectively, which project through the openings 27 and 28 as shown in Figure 5. A third screw 31 having access to the interior of the lower end of the chute below the screw 29 through the opening 32 in the chute is in cooperation with the 20 screws 29, 30 to hold the matrix properly erect and to push the same up the ramps 33, 34 which properly elevate the matrices so as to engage with the corresponding secondary distributing bar 35 which leads to the corresponding one of the magazines 8', 7', 6', 5', 4', 3', 2' and 1', as indicated 25 in Figure 4.

As the matrices drop through the chute, the lowermost one is stopped by engagement of one of each of the shoulders with the arm 36 of the latch generally designated 37 which consists of the J-shaped bar 38 which is pivoted on a suitable support as indicated at 39 and has the shorter arm 40 which like the arm 36 passes through an opening in the back of the part 25 40 of the chute. When the latch 38 is swung toward the left in Figure 5 the arm 36 will be withdrawn from the lower end of the matrix and permit the matrix to fall to the position in which the lowermost matrix is shown in Figure 5, while 45 the arm 40 engages between the vertically spaced shoulders on the next above matrix momentarily and then is withdrawn. As the latch 38, with the matrices positioned as shown in Figure 5 is swung toward the right, the arm 36 will be withdrawn from supporting relation to the lowermost matrix and permit the lowermost matrix to fall into the bottom 26 of the chute and into engagement with the screws 29, 30 and 31, so that the shoulders of the matrix engage in the grooves of 50 the screws and move toward the right, up over the ramps 33, 34 and on to the secondary distributing bar. The screw 29 has outwardly, that is to the left of the portion 41 of the chute 8, the cam 42 which is in operative relation with a 55 leg 43 of the latch 38, so as to operate the latch 38 in the manner already indicated at exactly spaced times, so as to effect controlled and intermittent feeding of the matrices 12 into engagement with the screws for transfer to the magazine 8'. The screws are driven by a conventional arrangement already known in the art, although presently used only with devices having two or four magazines only. Since each of the chutes of the mechanism is similar to the one just 60 scribed, it is believed that the description of each of the individual mechanisms is unnecessary.

It will be observed that the underside of the distributor bar 35 is V-shaped and provided with 75 teeth 44 which have a flat horizontal undersur-

face adapted to engage with the teeth 18, 19 of the matrices which have angulated lower surfaces. It will also be observed that certain portions of the teeth 44 on the bar 35 terminate at selected points as indicated at 45, 46, 47, 48, and 5 so on which discontinue in a manner to permit certain ones of the matrices to drop from the bar 35 in position to exactly enter one of the compartments 49 of the magazine 8', each of the compartments 49 corresponding to one of the letters of the alphabet or with one of the punctuation marks, or other marks or signs, according to the arrangement desired.

It will be understood that throughout the present description that each of the matrices is differentiated from the other not only by the arrangement of its shoulders and teeth but also by the arrangement of its teeth in the top notch thereof, so that the main distributing bar and the secondary distributing bars can only support any 20 given matrix until a point in the travel of the matrix thereon is reached whence the matrix should fall from the corresponding distributor bar into the corresponding chute or compartment of one of the magazines. 25

Reference to Figures 3 and 13 in conjunction with Figure 1 will give a proper idea of the construction and arrangement of the magazines and their relation to the chutes 1', 2', 3', 4', 5', 6', 7' and 8', and the secondary distributing bars which 30 deliver the matrices to the magazines.

Each magazine comprises a longitudinally elongated hollow member which is divided as indicated in Figure 4 into a multiplicity of compartments 49, and the magazines have a downward 35 and forward inclination as indicated in Figure 1, terminating at their lower ends in the delivery chutes generally designated 45 which empty onto the conveyor belt 46 which for convenience may be located above and to the rear of the key-board which is generally designated 47.

Each compartment of each magazine has at the lower end thereof an arm 48 which is pivoted near its lower end as indicated at 49 to a suitable support and has on opposite sides of the pivot the long arm 50 and the short arm 51 which are slidable through openings in the lower side of the compartment as shown in Figure 3. The lower end of the arm 49 has a weight 52 heavy enough to act as a counter-balance for the extended portion 53 which is in the form of an armature for operation by an electro-magnet 54 located on the underside of the magazine near the upper end thereof as shown in Figure 1. When the extended portion 53 of the arm 48 is 55 attracted and moved upwardly by its electro-magnet 54 the arm 51 will be pushed into the compartment 49 into a position between the shoulders of the adjacent matrix, while the arm 50 will be withdrawn from engagement with the upper shoulder of the adjacent matrix so as to permit the lowermost matrix in the compartment 49 to slide and fall into the curved portion 55 of the upper end of the delivery chute 45. When the magnet 54 is deenergized the weight 60 52 will not effect the return of the extended portion 53 to the depressed position shown in Figure 1, but will prevent the portion 53 from dropping too far, as will engagement of the arm 50 with an adjacent matrix. It will be obvious that the 65 momentary swinging of the arm 48 accompanied by its return to initial position will effect intermittent delivery of matrices in the compartment 49 into the upper end of the chute 45.

In order to prevent the matrices which fall 75

through the upper part of the chute 45 from catching in the opening of the next lower neck 56 which is fed by another compartment 49 equipped with a similar gate mechanism, I provide the 5 swinging gate 57 which is pivoted at its upper end as indicated at 58 to the top of the last-mentioned opening, so as to maintain the width of the passage in the chute unbroken to guide the falling matrices. The lower end of the gate 57 10 engages the lower part of the last-mentioned opening so as to resist movement by the matrices as they fall through the chute. However, matrices passing through the neck 56 move the gate 57 out of the way by swinging the gate toward 15 the front of the chute. Two of the gates 57 are shown in front elevation in Figure 13. The front of the chute 45 is equipped with a glass window through which the operator of the keyboard may 20 view the dropping of the matrices selected by him.

The keyboard generally designated 47 contains magazine keys 60 which are pivoted as indicated at 62 and have their rear ends under plungers 63 having a contact 64 engageable when 25 pushed upwardly with the contact 65, the plunger and the contact being mounted in a suitable block 66, so that when the key 60 is depressed the corresponding magazine switch will be closed to energize the electro-magnet corresponding thereto. 30 The numeral 60 is used to designate not only the magazine selecting key of the switch board but the switch as a whole which is operative upon pressing the key 60, while the letter selecting keys are each similarly designated 61 and regarded as a whole as a switch, especially in the 35 designation of the features of the wiring diagram in Figure 9.

In operating the device of the invention the magazine selecting key 60 is pressed which corresponds to the magazine containing the kind or size of letters or signs chosen, and then the letter selecting key 61 is pressed for the purpose of selecting the desired letter from the selected magazine. The effect of closing the switch 60 40 and then the letter selecting switch 61 is to energize the electro-magnet 54 corresponding to the selected one of the magazine, and particularly the electro-magnet 54 corresponding to the compartments 49 of the selected magazine 45 which contain the matrices having thereon the letters chosen; so that the respective gate mechanisms already described and shown in Figure 3 will be operated so as to release from the specified compartments of the selected magazine, the desired matrices which then fall through 50 the delivery chute 45 onto the conveyor belt 46 and are moved by the belt to the composition block and then to the mold or casting; followed by removal from the mold and return to the 55 magazines.

Although I have shown and described herein a preferred embodiment of my invention, it is to be definitely understood that I do not desire to limit the application of the invention thereto, and any change or changes may be made in materials, and in the structure and arrangement of parts, within the spirit of the invention and the scope of the subjoined claims.

What is claimed is:—

1. A device of the character described comprising a primary distributor bar provided with a channel in its lower side formed on its facing sides with longitudinal teeth, matrices having teeth on their lateral edges engaging with said longitudinal teeth, chutes into which said mat-

rices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the matrices. 5

2. A device of the character described comprising a primary distributor bar provided with a channel in its lower side formed on its facing sides with longitudinal teeth, matrices having teeth at the upper part of their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, 20 magazines into which the matrices drop from said secondary distributor bars as discontinuous portions of the second longitudinal teeth are reached by the matrices, said chutes 25 being perpendicular.

3. A device of the character described comprising a primary distributor bar provided with a channel in its lower side formed on its facing sides with longitudinal teeth, matrices having teeth on the upper part of their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, 40 said matrices being formed in their upper ends with toothed notches engaging said second longitudinal teeth, and magazines into which the matrices drop from said secondary bars as discontinuous portions of the second longitudinal teeth are reached by said matrices, said magazines having a portion provided with a selectively operable 45 gate. 50

4. A device of the character described comprising a primary distributor bar provided with a channel in its lower side formed on its facing sides with longitudinal teeth, matrices having teeth on their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the matrices, each of said magazines including a declining portion leading from under the 70 respective secondary distributor bar, and a perpendicular portion into which the depressed end of said declining portion leads. 65

5. A device of the character described comprising a primary distributor bar provided with a 75

channel in its lower side formed on its facing sides with longitudinal teeth, matrices having teeth on their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the matrices, each of said magazines including a declining portion leading from under the respective secondary distributor bar, and a perpendicular portion into which the depressed end of said declining portion leads, each of said magazines including a declining portion leading from under the respective secondary distributor bar, and a perpendicular portion into which the depressed end of said declining portion leads.

6. A device of the character described comprising a primary distributor bar provided with a channel in its lower side formed on its facing sides with longitudinal teeth, matrices having teeth on their lateral edges, engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the matrices, each of said magazines including a declining portion leading from under the respective secondary distributor bar, and a perpendicular portion into which the depressed end of said declining portion leads, each of said magazines including a declining portion leading from under the respective secondary distributor bar, and a perpendicular portion into which the depressed end of said declining portion leads, said gate including a pivoted magnetizable arm lying along said declining portion, an electromagnet on an upper part of said declining portion and in magnetic relation to the upper end of said magnetizable arm.

7. A device of the character described comprising a primary distributor bar provided with a channel in its lower side formed on its facing sides with longitudinal teeth, matrices having teeth on their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the matrices, each of said feeding means including a pair of spaced screws between which the matrices drop from the lower end of

the respective chute, stationary inclined cam means onto and along which the matrices are pushed by the screws into place on said secondary distributing bar.

8. A device of the character described comprising a primary distributor bar provided with a channel in its lower side formed on its facing sides with longitudinal teeth, matrices having teeth on their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the matrices, each of said feeding means including a pair of spaced screws between which the matrices drop from the lower end of the respective chute, stationary inclined cam means onto and along which the matrices are pushed by the screws into place on said secondary distributing bar, the lower end of said chute being equipped with gate means operating to hold the matrices in the lower end of said chute and to release the lowermost matrix into engagement with said screws between adjacent threads of said screws. 5 10 15 20 25 30

9. A device of the character described comprising a primary distributor bar provided with a channel in its lower side formed on its facing sides with longitudinal teeth, matrices having teeth on their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the matrices, each of said feeding means including a pair of spaced screws between which the matrices drop from the lower end of the respective chute, stationary inclined cam means onto and along which the matrices are pushed by the screws into place on said secondary distributing bar, the lower end of said chute being equipped with gate means operating to hold the matrices in the lower end of said chute and to release the lowermost matrix into engagement with said screws between adjacent threads of said screws, said screws having cam portions operatively engaging said gate means. 35 40 45 50 55 60

10. A device of the character described comprising a primary distributor bar provided with a channel in its lower side formed on its facing sides with longitudinal teeth, matrices having teeth on their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said mat- 75

rices having toothed notches in their upper ends engaging said second longitudinal teeth, and magazines into which the matrices drop from said secondary distributor bars as discontinuous portions of the second longitudinal teeth are reached by the matrices, each of said magazines including a declining portion leading from under the respective secondary distributor bar, and a perpendicular portion into which the depressed end of said declining portion leads, each of said magazines including a declining portion leading from under the respective secondary distributor bar, and a perpendicular portion into which the depressed end of said declining portion leads, 10 said gate including a pivoted magnetizable arm lying along said declining portion, an electromagnet on an upper part of said declining portion and in magnetic relation to the upper end of said magnetizable arm, said magnetizable arm being pivotally supported intermediate its ends and formed at its lower end with a weight operating gravitationally to hold a member of said gate closed, while said electromagnet is in deenergized condition.

25 11. A device of the character described comprising a primary distributor bar provided with a channel in its lower side formed on its facing sides with longitudinal teeth, matrices having teeth on their lateral edges engaging with said longitudinal teeth, chutes into which said matrices are selectively dropped from discontinuous portions of said longitudinal teeth, longitudinal feeding means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the matrices, each of said feeding means including a pair of spaced screws between which the matrices drop from the lower end of the respective chute, stationary inclined cam means onto and along which the matrices are pushed by the screws into place on said secondary distributing bar, the lower end of said chute being equipped with gate means operating 25 to hold the matrices in the lower end of said chute and to release the lowermost matrix into engagement with said screws between adjacent threads of said screws, said screws having cam portions operatively engaging said gate means, 30 said cam portions being located exteriorly of the lower end of the chute.

35 12. A device of the character described comprising a primary distributor bar provided with a channel in its lower side formed on its facing sides 35 with longitudinal teeth, matrices having teeth on their lateral edges engaging with said longitudinal teeth, chutes into which said matrices are selectively dropped from discontinuous portions of said longitudinal teeth, longitudinal feeding 40 means at the lower ends of said chutes, secondary distributor bars in conjunction with said feeding means, said secondary distributor bars having second longitudinal teeth, said matrices having toothed notches in their upper ends engaging said second longitudinal teeth, and magazines into which the matrices drop from said secondary distributor bars as discontinuous portions of the second longitudinal teeth are reached by the 45 matrices, said primary distributor bar having a triangular guiding rib depending in said channel, said rib being smooth and being engaged in the toothed notches of said matrices.

55 JOSÉ MIDULLA FLOREZ.
